BURNISHING TOOL

Alfred H. Haberstump, Detroit, Mich., assignor to
The Murray Corporation of America, Detroit,
Mich., a corporation of Delaware

Application September 30, 1942, Serial No. 460,319

9 Claims. (Cl. 29—90)

This invention relates to burnishing tools, and particularly to a burnishing tool for ironing metal at the sides of a scratch mark into the scratch cavity, and sealing and polishing the surface thereafter.

The present invention is an improvement on the burnishing tool illustrated, described and claimed in the copending application of R. D. Stephens, Serial No. 459,417, filed September 23, 1942, and assigned to the assignee of the present invention.

The burnishing tool is employed for filling, sealing, and polishing the scratch marks which appear in metal or other material, and particularly in clad metal employed as the covering material or "skin" of airplanes. The clad material has a center core of aluminum alloy and an outer surface layer of pure aluminum which protects the inner metal from oxidation. When a scratch is made upon this material the inner metal is exposed directly to oxidation, and, to prevent the scrapping of the sheet, the present tool successfully burnishes and seals the scratch mark. The metal is ironed into the body of the mark and forced into intimate sealing relation, and the surface is thereafter polished.

The present tool incorporates a set of spring-pressed wheels which are preferably made of rubber, or a similar material embodying friction properties, which engage the metal surface on each side of the scratch mark for steadyng the tool and guiding the burnishing head along the mark. The head is disposed in off-center relation to the axis of its shank, which tends to transfer some of the oscillating movement to the tool when in contact with the work. The rubber or similar wheels grasp the surface of the sheet and prevent any oscillating movement from being transferred from the burnishing head to the driving portion of the tool. Thus, all of the movement applied to the burnishing head will be utilized in working the metal on both sides of the scratch mark thereinto and into sealed relation.

Accordingly, the main objects of the invention are: To provide a tool with a burnishing head mounted in offset relation to the axis of the tool and with spring-pressed wheels for stabilizing the tool operation; to provide a tool having a right angled driving head with a burnishing tip which is in off-center relation to its shank and a spring-pressed support for a wheel which extends below the burnishing tip; to provide a burnishing tool having a head in off-center relation to the axis of its shank with a hardened tip of segmental

spherical form for working the metal on each side of a scratch mark without undue wear to the tip; and, in general, to provide a burnishing tool with a pair of guiding and stabilizing wheels and with a hardened burnishing tip.

Other objects and features of novelty of the invention will be either specifically pointed out or will become apparent when referring, for a better understanding of the invention, to the following description, taken in conjunction with the accompanying drawing, wherein:

Figure 1 is a view in elevation of a burnishing tool embodying features of this invention, with the burnishing tip out of contact with the mark to be burnished;

Fig. 2 is an end view of the tool illustrated in Fig. 1;

Fig. 3 is a broken view of the tool illustrated in Fig. 1, with the burnishing tip in engagement with the mark; and

Fig. 4 is a broken sectional view of the structure illustrated in Fig. 2, taken on the line 4—4 thereof.

Figure 1 illustrates a pneumatically operated tool 5 of conventional form, having a driven collet 6 disposed at right angle to the body portion 7 thereof. Air or other fluid is introduced into the body through the inlet opening 8 controlled by a lever 9 operating a valve stem 11. The collet 6 supports the burnishing tool 12 having a shank 13 and a burnishing head 14. The axis of the head 14 is offset from the axis of the shank 13 and is of segmental, spherical shape so as to have a point engagement with the metal. The point passes across the metal at both sides of the mark and works the metal into the base and into sealing relationship.

A bracket 15 is clamped to the body portion 7 of the tool by a cap 16 and bolts 17. The bracket has a bifurcated end 18 in which a wheel supporting element 19 is secured on a pivot 21. The end 22 of the element 19 has an aperture 23 in which one end of a spring 24 is secured, the other end being secured in an aperture 25 in the bracket 15. The opposite end 26 of the element 19 is bifurcated, providing a pair of spaced arms 27 and 28 between which a pair of wheels 29 are supported on pins 31. The spring 24 draws the end 22 upwardly to have the wheels 29 disposed below the burnishing end 14 of the tool in position to engage a sheet 32 to be burnished before the head 14 comes into contact therewith, as illustrated in Figs. 1 and 2.

Further pressure applied to the body portion 7 moves the head downwardly against the tension

of the spring 24 and applies a predetermined pressure between the wheels 29 and the surface of the sheet 32. Sufficient friction will then exist between the wheels 29 and the surface to prevent the movement of the eccentric end 14 from oscillating the tool body during the burnishing operation. The wheels, besides stabilizing the tool, assist in guiding the head 14 backwardly and forwardly along the scratch mark as the burnishing operation progresses.

A felt roller 34 mounted on a bushing 35 is secured on a shaft to the extensions 36 of the arms 27 in position to engage the sheet 32 when the tip 14 engages the scratch mark. Lubricating material is carried by the felt roller which provides lubrication to the mark and tip to prevent the gouging of metal by the tip and the wearing of its point.

The degree of eccentricity of the head 14 to the axis of the tool shank 13 may be varied in different tools, depending upon the width of the scratch marks or the width of the path to be burnished. In Fig. 4, a section of the burnishing head 12 is illustrated with the shank portion 13 made of mild steel or similar material while the tip portion 14 secured thereto is made of extremely hard material, such as Stellite, tungsten, and the like. The hardened tip substantially eliminates any wear to the end of the tool and materially increases the tool's life.

When a scratch mark 33 is to be burnished, the wheels are disposed upon the sheet 32 equally spaced on either side of the mark. This will align the axis of the shank 13 with the mark so that the eccentric point of the tip 14 will travel beyond both sides of the mark. The tool is then pressed downwardly to have the burnishing tip 14 engage the surface of the sheet and, when rotated at high speed, on the order of 5,000 R. P. M., the material at the sides of the scratch will be worked into the base of the scratch and into sealed relation. Thereafter, the surface may be polished by the application of light pressure to the tool as the tool is moved back and forth across the mark as it is guided by the wheels. It was found that a light scratch mark can be completely burnished by the tool from the sheet and polished in the course of one to two minutes' operation.

What is claimed is:

1. A burnishing tool having a tip mounted in offset relation with its shank, a spring-pressed wheel extending beyond the tip for guiding and stabilizing the tool during operation, and means for driving said tool in rotation about the axis of the shank to have the burnishing point of the tool describe a circle thereabout.

2. In a burnishing device, a driven tool supporting element, a tool supported by said element having a burnishing end mounted eccentrically to the center of the tool shank, a bracket on said device, an element pivoted on said bracket extending adjacent to the tip, a wheel on the end of the element projecting below the tip, and a spring urging said wheel away from the tip to have the wheel engage the surface of the material with a predetermined pressure when the tool engages said surface.

3. A burnishing device including, in combination, a driving element, a driven element, a burnishing tool supported by said driven element having a head in eccentric relation to the axis of the tool shank, a bracket supported on said driving element, a bifurcated member pivoted on the bracket, a pair of spaced wheels supported on the bifurcated end of the said member disposed on opposite sides of the burnishing head, a spring on the opposite end of said member for urging said wheels below the burnishing head, and means for controlling the operation of the driving element.

4. In a burnishing device, a driving portion, a driven portion disposed at right angle thereto, a burnishing tool supported by said driven portion, a bracket on said driving portion, a bifurcated element pivoted on said bracket, wheels disposed in the bifurcated end of said element on opposite sides of said burnishing tool, and a spring on the opposite end of said element in position to move the end of the element supporting the wheels downwardly to have the wheels disposed below the end of the burnishing tool.

5. A burnishing device including a driving portion, a portion driven thereby, a burnishing tool driven by said driving portion, said burnishing tool having a head in off-center relation to the axis of its shank which is made of a material harder than the shank portion for working the metal on both sides of a cavity toward the center thereof.

6. The method of burnishing the metal at the sides of scratch marks which includes the steps of; working the metal at the sides of the mark toward the center by a point rotating in a circle across the mark, and guiding the burnishing operation by frictionally engaging the surface outwardly of the mark during the burnishing operation.

7. The method of burnishing a scratch mark which includes the steps of, rotating a point across the sides of the mark, and stabilizing the operation and guiding the movement of the points along the mark by frictionally engaging the surfaces on both sides of the mark with a predetermined pressure.

8. A burnishing tool having a tip mounted in offset relation to its shank, means for rotating said shank, a spring pressed wheel extending beyond the tip for guiding and stabilizing the tool when the tip is operating on the surface of a sheet, and a lubricating element contacting said sheet adjacent to said tip.

9. In a burnishing device; a driven tool supporting element, a tool supported by said element having a burnishing end mounted eccentrically to the center of the tool shank, a bracket on said device, a member pivoted on said bracket extending adjacent to the tip, a wheel on the end of said member, a lubricating roller also mounted on said member, and a spring urging said wheel and roller away from the tip to have the wheel and roller engage the surface of the material with a predetermined pressure when the burnishing end of the tool engages said surface.

ALFRED H. HABERSTUMP.
